UNITED STATES PATENT OFFICE

158,237

COMBINED BOTTLE AND CAP

Northam Warren, Jr., New Canaan, Conn., assignor to Northam Warren Corporation, Stamford, Conn., a corporation of New York

Application October 1, 1948, Serial No. 148,900

Term of patent 14 years

(Cl. D58—8)

To all whom it may concern:

Be it known that I, Northam Warren, Jr., a citizen of the United States, residing at Silvermine Road, New Canaan, in the county of Fairfield, and State of Connecticut, have invented a new, original, and ornamental Design for a Combined Bottle and Cap, of which the following is a specification, reference being had to the accompanying drawing, forming part thereof.

In the drawing

Fig. 1 is a front elevational view of a combined bottle and cap, showing my new design;

Fig. 2 is a side elevational view of the combined bottle and cap; and

Fig. 3 is a top plan view thereof.

I claim:

The ornamental design for a combined bottle and cap, substantially as shown.

NORTHAM WARREN, JR.
